(Cl. D58—12.6)

To all whom it may concern:

Be it known that we, Lawrence H. Singer and Lewis S. Utley, citizens of the United States, residing at Brooklyn, State of New York, and Forest Hills, State of New York, respectively, have invented a new, original, and ornamental Design for a Plastic Display Case, of which the following is a specification, reference being had to the accompanying drawing, forming a part hereof.

Fig. 1 is a top plan view of a plastic display case embodying our new design;

Fig. 2 is a front elevation view thereof;

Fig. 3 is an end elevation view thereof; and

Fig. 4 is a fragmentary view in section taken along the line 4—4 of Fig. 1 to an enlarged scale.

We claim:

The ornamental design for a plastic display case, substantially as shown.

LAWRENCE H. SINGER.
LEWIS S. UTLEY.
